UNITED STATES PATENT OFFICE.

ROBERT E. CECIL, OF SEWICKLEY, PENNSYLVANIA, ASSIGNOR TO AIR-TIGHT STEEL TANK COMPANY, OF PITTSBURGH, PENNSYLVANIA, A CORPORATION OF PENNSYLVANIA.

SPRAYER-NOZZLE.

1,229,030.

Specification of Letters Patent. Patented June 5, 1917.

Application filed November 13, 1913. Serial No. 800,767.

To all whom it may concern:

Be it known that I, ROBERT E. CECIL, a citizen of the United States, and resident of Sewickley, in the county of Allegheny and State of Pennsylvania, have invented a new and useful Improvement in Sprayer-Nozzles, of which the following is a full, clear, and exact description, reference being had to the accompanying drawings, forming part of this specification, in which—

Figure 1 is a longitudinal sectional view of one form of nozzle.

Fig. 2 is a similar view of another form of nozzle.

Fig. 3 is an end view of the nozzle shown in Fig. 2.

Fig. 4 is a sectional view on the line VII—VII of Fig. 2, and

Fig. 5 is a sectional view of one of the nozzle disks.

My invention has relation to sprayer nozzles, more particularly designed for use in connection with spraying apparatus for trees and other vegetation, although it may be employed for other purposes.

The object of my invention is to provide a simple form of nozzle by means of which the liquid can be effectively sprayed.

The nature of my invention will be best understood by reference to the accompanying drawings in which I have shown two different modifications, and which will now be described, it being premised, however, that various changes can be made in the details of construction and arrangement of the various parts without departing from the spirit and scope of my invention as defined in the appended claims.

Referring first to that form of my invention which is shown in Fig. 1, the numeral 2 designates a nozzle shell or casing. In this figure the nozzle is of twin form, having an extension 2^a. The shell or casing is provided with an inlet connection at 3 for air under pressure having an extension 3^a. The shell or casing is also provided with an inlet 4 for the liquid to be sprayed. This inlet opens into a chamber 5 in the extension 2^a. The chamber 5 surrounds the extension 3^a of the air inlet. The air inlet terminates short of the front end of the chamber and is partially closed by a screw plug 6 which has a discharge aperture 7 therethrough.

Seated in the front end of each chamber 5 is a plate or disk 8 which has portions

thereof struck upwardly as indicated at 9 to form two or more tangentially arranged discharge openings 10. In the construction shown, these discharge openings are arranged at opposite sides of the center of the disk and discharge in opposite directions into a space 11 between the plate 8 and another plate or disk 12. The plate or disk 12 is held away from the plate or disk 8 by means of a separator ring 13; and the two plates or disks are held in place by a retaining sleeve 14, which is screwed on the end of each branch 2^a of the shell or casing. The disk 12 has its central portion struck outwardly as indicated at 15. This outwardly struck portion is of oblong form and preferably extends between the two orifices 10 and in the same direction as the direction of discharge from said orifices 10. At the center of this outwardly struck portion 14 is a discharge orifice 15^a.

The operation will be readily understood. The air under pressure discharged through the plug 7 comes in contact with the relatively thin body of liquid between the forward end of said plug and the disk or plate 8. Portions of the liquid are forced by the air through the discharge openings 10 of said disk and into the space 11 intermediate the disks 8 and 12. The inner surface of the outwardly struck portion 15 is of concave form, converging toward the discharge orifice 15^a. The liquid is discharged through this orifice in a fan-like sheet lying in a plane which is substantially perpendicular to the plane of section of Fig. 4.

The form of sprayer nozzle shown in the other figures is substantially the same as the one above described. In these figures, 3^b designates the air inlet having the single passage 3^c, and 4^b designates the single inlet for the liquid to be sprayed and which discharges into the chamber 5^a. In this form the shell or casing may be constructed of a T-shaped fitting 16 into the rear end of which is screwed a disk or plug 17 carrying the inlet connection 3^b. The nozzle proper is carried by a tubular section 18 which is screwed within and forms an extension of the opposite arm of the T. The nozzle proper is of the same construction as in the form first described.

It will readily be understood by those familiar with the art that the shape of the various disks may be varied to meet different

requirements and the size, shape and position of the openings therethrough may be varied within the scope of my invention.

While I prefer to employ the two disks 8 and 12, good results may be obtained by omitting the disk 8 and using only the disk 12. For some purposes also the connection for air under pressure may be omitted, the liquid to be sprayed being forced into the 10 chamber 5 of the nozzle under pressure.

What I claim is:

1. A sprayer nozzle having an inner spraying member formed with two outwardly offset portions at opposite sides of 15 the nozzle center and extending in a tangential direction, each of said portions having a discharge opening at its inner end, and another spraying member in front of the inner spraying member, said last mentioned member 20 having a flat inner wall and a central recess of greater length than width and a central perforation, said recess having its inner surfaces converging toward said perforation, the length of said recess lying in the 25 same direction as the offset portions of the inner spraying member and between said portions; substantially as described.

2. A sprayer nozzle having a chamber for the liquid to be sprayed, a plate or disk 30 forming the front wall of said chamber and having portions thereof struck outwardly to form eccentrically located discharge openings arranged to discharge in a generally tangential direction, and another plate or 35 disk in front of and separated from the first named disk, the latter having a central discharge orifice and a central recess of greater length than width on its inner face communicating with said discharge orifice, the 40 length of said recess lying between the eccentrically located discharge openings in the other disk; substantially as described.

3. A sprayer nozzle having an inclosed chamber for the liquid to be sprayed, a plate 45 or disk forming the front wall of said chamber and having a portion thereof struck outwardly to form an eccentrically located discharge opening arranged to discharge in a generally tangential direction, a second plate 50 or disk in front of and separated from the said first named disk, the latter having a central discharge orifice with surfaces converging toward said orifice, said nozzle also

having a connection for a liquid leading to the chamber, and means for introducing air 55 into said chamber at a point adjacent to the center of the first disk to spray the liquid through the opening in the disk; substantially as described.

4. A sprayer nozzle having a central air 60 chamber, means for admitting air to said chamber, an annular liquid chamber surrounding said air chamber, means for admitting liquid to said annular chamber, a disk member forming the front wall of the 65 liquid chamber, there being a central opening from the air chamber extending into the liquid chamber, the air being arranged to impinge against said disk member, said disk member having a plurality of tangentially 70 arranged openings on opposite sides of the air discharge opening, a second disk-like member in front of the first disk-like member, there being a chamber between said disk members, said last mentioned disk member 75 having a central opening for the discharge of the combined oil and air; substantially as described.

5. A sprayer nozzle having a central air chamber, means for admitting air to said 80 chamber, an annular liquid chamber surrounding said air chamber, means for admitting liquid to said annular chamber, a disk member forming the front wall of the liquid chamber, there being a central opening from the air chamber extending into the liquid chamber, the air being arranged to impinge against said disk member, said disk member having a plurality of tangentially 85 arranged openings on opposite sides of the air discharge opening, and a second disk-like member in front of the first disk-like member, there being a chamber between said disk members, the last mentioned disk member 90 having a central opening and a flat inner 95 face, there being a recess in the central portions thereof, the walls of said recess converging toward the outlet opening; substantially as described.

In testimony whereof I have hereunto set 100 my hand.

ROBERT E. CECIL.
